(57) **CLAIM**

The ornamental design for a support bracket kit with mounting adapters, as shown and described.

DESCRIPTION

FIG. 1 is a front perspective view shown in an environment of use for a support bracket kit with mounting adapters showing my new design;

FIG. 2 is a front side view thereof;

FIG. 3 is a top side view thereof;

FIG. 4 is a bottom side view thereof;

FIG. 5 is a rear side view thereof;

FIG. 6 is a left side view thereof; and,

FIG. 7 is a right view thereof.

1 Claim, 5 Drawing Sheets
